COMBINATION HIGH AND LOW VOLTAGE
LAMP

Lee G. Daniels, Rockford, Ill.

Application February 13, 1933, Serial No. 656,495

24 Claims. (Cl. 171—97)

This invention relates to a new and improved lamp.

Ultraviolet and infra-red lamps are now available, each adapted to serve only the one purpose. 5 This necessitates having entirely too much equipment for the average household user, both from the standpoint of the outlay in money and the space taken up when the lamps are not in use. It is, therefore, the principal object of my invention to provide a three purpose lamp; that is, one adapted by virtue of its special construction for use as an ultraviolet, infra-red, or ordinary reading lamp, whereby to make all of these facilities available at a low cost well within the 10 reach of the majority of prospective purchasers and in such a compact and handy form as to be suitable for use in smaller homes and apartments and wherever storage space is an item to be considered.

20 Another object is to provide a lamp, the bulb carrying head of which is so constructed that low voltage is available through a step-down transformer when connected on a standard 110 volt lighting circuit, whereby to permit use therein of an ultraviolet mercury bulb or other low voltage appliance, the head being further constructed so that an adapter may be inserted therein to isolate the transformer and provide line voltage suitable for a reading lamp or an 25 infra-red lamp, or any other higher voltage appliance.

More generally stated, the aim of my invention is to broaden the range of usefulness of a sun-lamp by providing a specially constructed adapter 30 to fit in the socket thereof and enable the use of other bulbs, when desired.

The invention is illustrated in the accompanying drawings, in which—

Figure 1 is a side view of a lamp made in accordance with my invention;

Fig. 2 is an electrical wiring diagram therefor;

Fig. 3 is a section through the head with the adapter therein and showing an infra-red lamp bulb in place and indicating a reading lamp bulb in dotted lines;

Fig. 4 is similar view but showing the adapter removed and an ultraviolet lamp bulb in place;

Fig. 5 is a cross-section on the line 5—5 of Fig. 3, and

Fig. 6 is a section similar to Fig. 3 but showing a modified construction.

The same reference numerals are applied to corresponding parts throughout the views.

Referring first to Figs. 1 and 2, the lamp of my invention has a hollow standard 6 rising from a

hollow base 7, and preferably a flexible neck 8 is provided on the upper end of the standard carrying the head 9 in which the special socket hereinafter described is provided and on which the reflector 10 is mounted. As a matter of convenience in turning the lamp on or off, I prefer to have the extension cord 11 enter the standard 6 about halfway up from the base with the switch 12 disposed next to the standard where it may be easily reached by the user while sitting 10 or lying down. A step-down transformer 13 is mounted in the base so as to be out of the way and add weight to the base for stability. The three wires 14, 15 and 16 indicated in Fig. 2 as having connection with the transformer, are extended through the standard 6 to the head 9 for connection with the appropriate ones of the group of terminals indicated at 17. For the time being it will suffice to say that this group comprises terminals 18, 19 and 20 connected as indicated to the wires 14, 15 and 16, respectively. The line connections from cord 11 are with the wires 14 and 16 as shown. From this much description it will be seen that the terminal parts 18 and 19 are for low voltage, and the terminal parts 16 and 20 for high voltage. In the case of 20 low voltage use of the lamp, as for example with an ultraviolet lamp bulb cooperating with terminal parts 18 and 19, there is high voltage imposed on the primary 21 of the transformer 13, 25 the circuit being from one side of the line through the primary winding 21 to the other side of the line. Low voltage is secured by induction into the secondary winding 22 and is imposed on the 30 terminal parts 18 and 19 by reason of their connection with said winding through wires 14 and 16. In the case of high voltage use of the lamp, as for example, when a reading lamp bulb or 35 infra-red lamp bulb is connected across terminal parts 18 and 20, it is evident that the transformer 13 is isolated, the parts 18 and 20 being in direct 40 connection with the opposite sides of the line through wires 14 and 16. There will, of course, be a slight amount of "seepage" current flow because of the primary winding 21 of the transformer 13 being connected across the line, but 45 this loss is negligible.

Referring now to Figs. 3-5, it will be observed that the terminal parts 18 and 19 are portions of a socket secured to the rear wall of the head 9, as 50 by means of screws 23. The part 18 is the center terminal of this socket, which is like a conventional lamp socket, the only difference being that the threaded shell part 19 is of larger diameter than the shell of a standard lamp socket, and is 55

adapted to receive the threaded end 24 of an ultraviolet mercury bulb 25, as shown in Fig. 4. These bulbs are purposely made with a larger end than is provided on a conventional reading lamp bulb, so that the purchaser cannot insert the same into an ordinary light socket. Such handling would mean the destruction of the bulb, since its filament 26 is designed only for low voltage; about 32 volts upon closing the circuit and 12 volts after vaporization of some of the mercury present in the bulb. One end of the filament 26 is, of course, connected with the end 24 engaging the terminal 19, and the other end of the filament is connected with the tip terminal 27 engaging the terminal 18, as shown, thus completing the low voltage circuit through the bulb, using terminal parts 18 and 19. It is apparent that under these conditions the third terminal 20 of the group previously referred to is not used. It is mounted on the plate 28 of insulation material, fastened in the front part of the head 9, as by screws appearing in Fig. 5. The plate 28 has an opening 29 therein large enough to have the neck of the bulb pass freely therethrough, as appears in Fig. 4.

Referring to Figs. 3 and 5, I shall now describe how the terminal 20 is used in connection with an infra-red lamp bulb 30 or an ordinary reading lamp bulb 31, which operates on line voltage independent of any connection with the transformer 13. An adapter, indicated generally by the numeral 32, fits in the socket formed by terminals 18-19 and serves by contact with the terminal 20 to switch from low voltage to high voltage, that is, it makes electrical connection with conductors 14 and 16 and isolates the conductor 15. The adapter 32 comprises a plug 33 threading in the socket 18-19, and a socket 34 carried on said plug and arranged to enter the hole 29 in the plate 28 and have electrical contact with the terminal 20. The plug 33 is of insulating material so as to isolate the terminal 19 and its conductor 15, but a terminal 35 extends lengthwise through the center of the plug to establish electrical contact with the terminal 18, as shown. Now, when the bulb 30 or 31 is entered in the socket 34 of the adapter, its threaded end 36 makes contact with the wall of the socket in the usual way, and the tip 37 makes contact with the terminal 35, thus establishing electrical connection with the terminals 20 and 18, respectively. A shell 38 is provided as a housing for the socket 34 and is of metal to serve as a conductor between the terminal 20 and the socket. A rim 39 of insulation material is provided on the outer end of the shell 38 to permit handling the adapter 32 without danger of getting a shock. The center hole 40 in the reflector 10 is large enough to admit the adapter freely. The terminal 20, it will now be observed, is in the form of a coiled tension spring stretched between two screws 41 and 42 carried on the front of the plate 28. The conductor 16 has connection with the screw 42, and a short wire 43 extends from the screw 42 over to the screw 41, so that current flows through the spring 20 from both ends, instead of from only one end. In that way there is no likelihood of the spring heating up to the point of losing its tension. The spring is so disposed with respect to the opening 29 that it has to be forced out of the way when the adapter 32 is screwed in place, and there is, therefore, a good electrical connection established by reason of the pressure of the spring against the shell 38 of the socket 34.

The adapter 32, it will be observed, has the socket 34 of smaller size than the socket 18-19 so as to permit inserting a bulb having a smaller

sized threaded end than the bulb 25, ultraviolet mercury bulbs being made with a larger end than other bulbs, as stated before. Now, while the adapter 34 is constructed to provide for the insertion of a smaller bulb and one operating on different voltage, it should be understood that my invention is not to be regarded as limited to that type of adapter alone, but might be embodied in an adapter providing for either a different sized bulb or a bulb to operate on different voltage. That is to say, the adapter might be of the form shown in Fig. 6 making connection with terminals 18 and 19 instead of 18 and 20, in which event the bulb inserted in the adapter will, of course, operate on the same voltage as a bulb inserted in the permanent socket, except that a low voltage bulb inserted in the adapter will operate continuously on about 32 volts and not be subject to a drop in voltage, like a sunlamp bulb, which, as stated before, starts on about 32 volts and, as soon as heated, uses about 12 volts. On the other hand, the adapter may be of a form making connection with terminals 18 and 20, without necessarily providing for the insertion of a different sized bulb.

Referring to Fig. 6, the adapter 32' has a socket 34' of smaller size than the socket 18-19 so as to permit inserting an ordinary 32 volt bulb 31 for reading purposes. The terminal 20 and plate 28 previously described are omitted in this form of the invention because this adapter 32' is constructed to make connection only with terminals 18 and 19. Terminal 35 on the plug 33' contacts the terminal 18 as shown. The shell 38' provided as a housing for the socket 34' makes contact with the terminal 19, as shown. Thus, in operation, a 32 volt bulb 31 inserted in the adapter 32' will operate continuously at 32 volts by reason of electrical connection with terminals 18 and 19. There is no drop in voltage under such circumstances as in the case of a sunlamp bulb. A change in voltage with those bulbs is due to the vaporization of some of the mercury present in the bulb, when the same gets heated. It is manifest that with an adapter such as the adapter 32' the lamp construction need not be changed to include the additional terminal 20 shown in Fig. 3. In other words, this adapter is applicable to existing sunlamps and enables the owner to use low voltage bulbs for reading purposes.

It is believed the foregoing description conveys a good understanding of the objects and advantages of my invention. The appended claims have been drawn with a view to covering all legitimate modifications and adaptations.

I claim:

1. A high-low voltage lamp comprising a head adapted to support a lamp bulb, three electrical conductors extended to the head, the first and third conductors arranged to have line voltage impressed thereon, a step-down transformer having the primary winding thereof connected across the first and third conductors and the secondary winding thereof connected across the first and second conductors, means in said head to receive the lamp bulb comprising insulated terminals for electrical connection with the bulb, and means for selectively rendering effective only the first and third or the first and second conductors in connection with the terminals, the first and third giving high voltage independent of the transformer and the first and second giving low voltage in accordance with the ratio of said transformer.

2. A high-low voltage lamp comprising a head adapted to support a lamp bulb, three electrical conductors extended to the head, the first and third conductors arranged to have line voltage impressed thereon, a transformer having the primary winding thereof connected across the first and third conductors and the secondary winding thereof connected across the first and second conductors, means in said head to receive 10 the lamp bulb comprising insulated terminals for electrical connection with the bulb, and means for selectively rendering effective only the first and third or the first and second conductors in connection with the terminals, the first and third giving one voltage and the first and second giving a different voltage, depending on the ratio 15 of the transformer.

3. A high-low voltage lamp comprising a head adapted to support a lamp bulb, three electrical conductors extended to the head, the first and third conductors arranged to have line voltage impressed thereon, a transformer having the primary winding thereof connected across the first and third conductors and the secondary winding thereof connected across the first and second conductors, means in said head to receive a lamp bulb comprising three insulated terminals connected respectively with the three conductors, the first and second terminals being constructed to receive a low voltage lamp bulb therebetween, independent of electrical connection with the third terminal, and an adapter constructed to receive a high voltage lamp bulb and connect the same with the first and third terminals, independent of electrical connection with the second terminal.

4. In combination, a lamp socket having two insulated terminals, and a plug adapted to be removably entered in said socket, said plug comprising a body of insulation material for isolating one of the two terminals of said socket, and a center terminal on the plug for electrical connection with the other terminal of said socket, and a companion terminal on the plug for the center terminal to form a secondary lamp socket.

5. In combination, a reflector, a casing behind a central opening provided therein, a lamp socket in said casing adapted directly to receive therein a lamp bulb entered in said opening and projecting in front of said reflector, a plug entered in said socket so as to connect with one of the terminals of the socket while isolating the other, a socket on said plug adapted to receive a lamp bulb therein projecting in front of said reflector, said socket providing a third terminal as a companion to the live terminal of the first socket, means for impressing a certain voltage across the terminals of the first socket, and means for impressing another voltage across the terminals of the other socket.

6. In a lamp of the character described comprising a socket adapted normally to receive a low voltage lamp bulb, conductors for supplying electric current at line voltage, a transformer connected therewith, other conductor means connected with the transformer for supplying electric current at below line voltage to said socket for said low voltage lamp bulb, a secondary socket mounted in said first socket so as to isolate the low voltage conductor means, and other conductor means connected with the line conductors for supplying electric current to said secondary socket at line voltage.

7. In a structure of the class described, a casing, two electrically insulated terminal members

rearwardly disposed with respect to the open front of said casing, said members being parts of a lamp socket, a third terminal member in said casing in front of the other terminal members, and a second lamp socket carried on a plug constructed for entry removably in the first socket, the second socket comprising two terminal members electrically insulated with respect to each other, the one being disposed so as to be brought into electrical contact with one of the first two 10 terminal members when the plug is entered in the first socket and the other being disposed so as to be brought into electrical contact with the third terminal member at the same time, there being electrical conductors permanently connected with the first three mentioned terminal members whereby to supply electric current to either of the sockets.

8. In an electric socket for lamps or the like, a casing, a pair of different sized sockets for interchangeable use in said casing, the one being permanently mounted in said casing and the other having a plug portion thereon for entry in the first socket for removably mounting the same in said casing, electrical conductors connected with the permanent socket mounted in the casing, terminal means mounted in the casing so as to have electrical connection with the second socket when the same is entered in the first socket, and additional electrical conductor means for 30 said terminal means.

9. In an electric socket for lamps or the like, a casing, a pair of different sized sockets adapted for interchangeable use in said casing, the one being permanently mounted in said casing and 35 the other having a plug arranged to be removably received in the first socket, electrical conductors for the first socket, said plug having a terminal thereon disposed so as to make electrical connection with one of the conductors of the first 40 socket when the second socket is mounted thereon, a terminal carrying plate permanently mounted in the casing in front of the first socket and having an opening provided therein to receive the second socket when the same is mounted 45 in the first socket, so as to make electrical connection with the other terminal of the second socket, and a separate electrical conductor connected with the terminal on said plate.

10. A structure as set forth in claim 9 where- 50 in the terminal on said plate comprises a tension spring disposed so as to have sliding electrical contact with the second socket when the same is entered in the opening in said plate, the conductor for said terminal having electrical connection with opposite ends thereof for the purpose 55 described.

11. In an interchangeable lamp, a casing, a relatively large two-terminal socket permanently mounted in said casing capable of receiving the 60 shank portion of a sunlamp with a working fit, a plug constructed like the shank portion of such a lamp for entry removably in said socket, a smaller sized two-terminal socket carried on said plug and capable of receiving the smaller shank 65 portion of an ordinary electric light bulb or an infra-red lamp with a working fit, a low voltage electrical conductor permanently connected with one of the terminals of the first socket, a high 70 voltage electrical conductor electrically connected with one of the terminals of the second socket, a third electrical conductor common to both the high and low voltage conductors connected with the other terminal of the first mentioned socket, the other terminal of the second 75

socket in said plug being disposed so as to make electrical connection with the last mentioned conductor when the plug is entered in the socket.

12. In a lamp of the character described, a permanent socket, electrical conductors for supplying electric current at different voltages, an adapter socket constructed for entry removably in said permanent socket, the adapter socket being adapted to receive lamp bulbs or other appliances, certain of the conductors being effective for the permanent socket, and means engageable by said adapter socket when entered in said permanent socket arranged to render different conductors operative.

13. In a lamp of the type described having a transformer and three terminals, a permanent socket constituting two of said terminals, and means cooperating with the permanent socket to render effective a third terminal in association with one of the terminals of the permanent socket, two of the three terminals giving line voltage independently of the transformer and another two of the three terminals giving a different voltage through the transformer.

14. In an all purpose lamp, in combination with a transformer, a permanent socket, an adapter socket adapted to be entered removably in the permanent socket, means providing electrical connections between the transformer and the permanent socket permitting use in said socket of an ultraviolet lamp bulb or the like operating at less than line voltage, and means providing connections independent of the transformer with the adapter socket permitting use in said socket of infra-red, therapeutic, or lighting lamp bulbs operating at line voltage.

15. In an all purpose lamp, in combination with a transformer connected with line conductors, a permanent socket, an adapter socket entered removably in the permanent socket, means providing electrical connections between the transformer and the permanent socket permitting use in said socket upon removal of the adapter socket of an ultraviolet lamp bulb or the like operating with a variable voltage through said transformer, and means providing electrical connections through the adapter socket with the transformer permitting use in said socket of other lamp bulbs or the like operating with substantially constant voltage.

16. In a device of the character described, in combination with a transformer connected with line conductors, a permanent socket, an adapter socket, means providing connections between the transformer and the permanent socket for operation in said socket of an appliance at a voltage differing from the line voltage in accordance with the transformer ratio, and means providing connections between the adapter socket and the line conductors through the permanent socket whereby to permit operation of an appliance at line voltage inserted in the adapter socket.

17. In a device of the character described, in combination with a transformer connected with line conductors, a permanent socket, an adapter socket, means providing connections between the transformer and one of said sockets to supply the same with voltage different from line voltage, and means providing connections between the line conductors and the other socket independently of the transformer to supply the same with line voltage, whereby to permit operation in the one device of appliances at line voltage or appliances at another voltage differing from line voltage in accordance with the transformer ratio.

18. In an ultraviolet lamp, in combination with a transformer connected with line conductors, a permanent socket of a special larger size adapted for use therein of an ultraviolet lamp bulb and electrically connected with the transformer for that purpose, an adapter socket of a smaller size suitable for use therein of ordinary lamp bulbs and screwed removably into the permanent socket, said adapter socket having a flange of non-conducting material on the outer end to be gripped in the hand in the insertion of said socket, and means providing electrical connections for the adapter socket through the permanent socket with said transformer.

19. In a lamp of the type described, line conductors, a transformer connected therewith, a permanent stationary socket and a removable adapter socket screwed into the permanent socket, and means providing connections between the sockets and the line conductors and transformer to supply one of said sockets with low voltage and the other with line voltage whereby to permit operation in one of said sockets of an ultraviolet lamp bulb of low voltage, and use in the other socket of a lamp of higher voltage.

20. A device of the class described comprising in combination a reflector, a housing for a lamp socket structure behind an opening provided in the reflector, a permanent socket in said housing at a predetermined distance from the opening adapted directly to receive an elongated lamp bulb entered in the opening and projecting in front of said reflector, an adapter socket having a plug portion removably received in the permanent socket so as to support the adapter socket closer to the reflector opening, whereby it is adapted to receive a shorter lamp bulb therein projecting in front of said reflector, and electrical conductors electrically connected with the socket structure.

21. A device of the class described comprising in combination a reflector, a housing for a lamp socket structure behind an opening provided in said reflector, a permanent socket in said housing adapted normally to receive a sunlamp bulb entered through the opening and projecting in front of the reflector, conductors for supplying electric current at a certain line voltage, a transformer connected therewith, conductors connected with the transformer and having electrical connection with said socket to operate a sunlamp bulb at variable low voltage, and a secondary socket removably mounted in the permanent socket and entered in said permanent socket through the aforesaid reflector opening, the secondary socket having electrical connection with the first socket and adapted to receive other lamp bulbs and support the same projecting in front of the reflector.

22. A device of the class described comprising in combination a reflector, a housing for a lamp socket structure behind an opening provided in said reflector, a larger sized permanent socket in said housing spaced from the opening sufficiently to permit entering only an elongated sunlamp bulb having the required larger sized shank to fit in said socket, and prevent entering other bulbs, an adapter socket having a proper sized plug portion to enter the permanent socket, the adapter socket being smaller sized and of the proper length to reach to a predetermined close proximity to the reflector opening when mounted in the permanent socket, whereby it will receive lamp bulbs having smaller sized shank portions and support the same projecting in front

of the reflector, and prevent entering a sunlamp bulb, and electrical conductors electrically connected with the socket structure.

23. A device of the class described comprising in combination a reflector, a housing for a lamp socket structure behind an opening provided in said reflector, a lamp socket in said housing at a predetermined distance from the opening so as to receive a certain elongated bulb entered through the opening and projecting in front of the reflector to a predetermined distance, electrical conductors electrically connected with said socket, a separate terminal member mounted in the housing between the socket and the opening so as to permit free entry into said socket of the aforesaid lamp bulb but make electrical connection with an adapter when substituted for the

lamp bulb, and other electrical conductor means electrically connected with the terminal member.

24. A device of the class described comprising, in combination, a reflector having an opening provided therein, a permanent socket disposed behind and spaced from the reflector in approximately coaxial alignment with said opening, a transformer connected with the socket and normally arranged to operate a sunlamp bulb therein at variable low voltage, and an adapter entered 10 in said socket and projecting toward the opening in the reflector and having a socket disposed in a different relation to the reflector than the first mentioned socket and adapted to receive an electric light bulb arranged to operate at substantially constant low voltage. 15

LEE G. DANIELS.
